UNITED STATES PATENT OFFICE.

BROOKING T. HICKMAN, OF KANSAS CITY, MISSOURI.

DRYING-TUMBLER.

1,243,603.

Specification of Letters Patent.

Patented Oct. 16, 1917.

Application filed January 22, 1917. Serial No. 143,588.

To all whom it may concern:

Be it known that I, BROOKING T. HICKMAN, a citizen of the United States, residing at Kansas City, in the county of Jackson and State of Missouri, have invented certain new and useful Improvements in Drying-Tumblers, of which the following is a specification.

My invention relates to improvements in 10 drying tumblers, for use in laundries, dry-cleaning establishments, etc., and one object is to provide a simple, efficient and inexpensive machine of this character whereby garments, etc., can be dried more quickly 15 and economically than with the machines now in general use.

Heretofore, drying tumblers have been heated with steam coils placed more or less remote from the cylinder in which the garments are dried. Exposure of said coils to 20 the air cools the steam passing therethrough and results in considerable condensation which renders the steam inefficient for heating purposes. Considerable loss of heat 25 radiated from the coils also results in their comparative remoteness from the garments being dried, so that on the whole only a small percentage of efficiency is obtained from the fuel employed.

I overcome the foregoing objections by applying the heat directly around the cylinder where it will prove most effective, and reduce to a minimum trouble from condensation of steam.

In order that the invention may be fully understood, reference will now be made to the accompanying drawings, in which:

Figure 1 is a side elevation of a drying tumbler constructed in accordance with my 40 invention.

Fig. 2 is a detail perspective view of a plurality of steam chests constituting an important feature of the invention.

Fig. 3 is a central, vertical section of the 45 drying tumbler, taken on line III—III of Fig. 4.

Fig. 4 is a central, cross section, taken on line IV—IV of Fig. 3.

Fig. 5 is a modified form of steam chest.

In carrying out the invention, I employ a 50 cylinder casing 1, provided with a door 2 and carried by a frame 3 having a plurality of legs 4.

55 Fig. 5 designates a rotary cylinder arranged within the casing 1 and consisting of foraminous material to permit the circulation of

hot air therethrough. Said cylinder 5 is provided with a pair of trunnions 6, journaled in bearings 7 on opposite sides of the casing 1, one of said trunnions 6 having a loose pulley 8 and a fixed pulley 9 through which latter the cylinder 5 is driven.

The cylinder 5 is provided with a peripheral door 10 controlling access to the interior thereof for the placement and removal of garments and other articles to be dried after being cleaned. Said door 10 may be mounted in any suitable manner. In the drawings, I have shown it operably-connected at one end to the cylinder by a hinge 11 and provided at its free end with a suitable fastening device 12, whereby it may be secured in closed position.

13 designates a plurality of segmental steam chests placed around the interior of the casing 1 in an annular space 14 left between said casing 1 and the cylinder 5 for the purpose. The steam chests 13 are connected by steam pipes 15, 16, and 17, so that steam admitted through an inlet pipe 18 may freely flow to the different chests to heat the same before finally escaping through an exhaust pipe 19 communicating with one of the lower steam pipes 16. As disclosed by Fig. 2, the two uppermost steam 85 chests 13 are spaced a considerable distance apart, such space being opposite the door 2 in the casing to permit access to the cylinder 5 when its door 10 is opposite said door 2.

21 designates an air inlet duct communicating at its lower end with two branches 22 leading into opposite sides of the casing 1 near the upper portion thereof, and 24 designates two outlet ducts leading from the lower portion of the casing 1 near the opposite sides thereof to a fan or blower 25, the shaft of which is provided with a loose pulley 27 and a fixed pulley 28, through the intermediacy of which latter said shaft is driven.

The steam pipe 18 may receive its supply of steam from any suitable source. In Fig. 1 of the drawings, I have shown it communicating with a boiler A to which the exhaust steam can be returned if desired through the pipe 19.

In practice the cylinder 5 is rotated until its door 10 is opposite the door 2 of the casing 1, so that garments or other articles can be placed in said cylinder. The doors are then secured in closed position, the cylinder

5 is rotated at a suitable speed, and steam is admitted to the steam chests from the inlet pipe 18. The blower 25 is also started to draw air through the cylinder 5 and the contents thereof. As the air passes through the cylinder 5 it is highly heated by direct contact with the steam chests 13 and thus quickly accomplishes its function of drying the articles in the cylinder, which, through its rotary motion, agitates and moves the articles about, thus exposing the different parts thereof to the hot current of air passing through the cylinder.

By applying the heat directly within the cylinder casing 1 instead of through exterior coils as is customary, it is obvious that the steam is employed in the most economical and efficient manner, which in effect increases the capacity of the apparatus, as it is apparent that a greater number of articles can be dried in a given period of time than heretofore.

While the apparatus is efficient in drying clothes which have either been laundered, or dry-cleaned with gasoline in the usual way, it can be employed to advantage in drawing lint and dust from the garments before they are placed in a gasoline vat for cleaning, hence the same gasoline may be used over and over again to a greater extent than heretofore.

For convenience in assembling the parts the steam chests 13 are made small enough to pass through the doorway in the casing 1, but it is obvious that one large steam chest 3^a can be used instead of several small ones, if placed in the casing before the ends thereof are closed.

From the foregoing description it is apparent that I have produced an efficient apparatus embodying the advantages above enumerated, and while I have shown and described the preferred form of my invention, I reserve the right to make such changes in the construction, proportion, and arrangement of parts as properly fall within the spirit and scope of the claims.

Having thus described my invention, what I claim and desire to secure by Letters Patent, is:

1. In a machine of the character described, a casing having a door therein, a cylinder of foraminous material journaled in said cas-

ing and provided with a door, a steam chest interposed between the walls of said casing and the cylinder, and means for creating an air current through the casing and the cylinder and against said steam chest.

2. In a machine of the character described, a casing having a door therein, a cylinder of foraminous material journaled in said casing and provided with a door, a plurality of steam chests interposed between the walls of said casing and the cylinder, two of said steam chests being spaced apart opposite the door of the casing, steam pipes connecting said steam chests, and means for creating an air current through the casing and the cylinder and against said steam chests.

3. In a machine of the character described, a casing, means through which access may be had to the interior of said casing, a cylinder journaled in said casing, means through which access may be had to the interior of said cylinder, a steam chest interposed between the walls of the casing and the cylinder, air inlet pipes communicating with the casing, air outlet pipes also communicating with said casing, and a blower connected to certain of said pipes to create an air current through the casing and the cylinder and against the steam chest.

4. In a machine of the character described, a casing having means of access to the interior thereof, a cylinder journaled in the casing and provided with means whereby access may be had to the interior of said cylinder, means for rotating said cylinder, a steam chest interposed between the walls of the casing and the cylinder, means for conducting steam to said steam chest, means for exhausting steam from said steam chest, air inlet pipes communicating with the upper portion of the casing, air outlet pipes leading from the lower portion of the casing, and a blower connecting certain of said pipes to create a circulation of air through the casing and the cylinder and against the steam chest.

In testimony whereof I affix my signature, in the presence of two witnesses.

BROOKING T. HICKMAN.
